DRY SHAVER

Norman J. Trought, Kearny, N. J.

Application December 7, 1948, Serial No. 63,892

8 Claims. (Cl. 30—43)

1

This invention relates generally to dry shavers and more particularly to a hand operated dry shaver.

In brief, this invention comprises a hand operated drive mechanism enclosed in a casing having two complementary hollow sections, there being provided novel means whereby the frame of the mechanism is used to secure the adjacent ends of the casing sections at one end of the casing, while the other end of the casing is provided with a cutter head shield adapted to cover screws used to secure the corresponding ends of the casing sections together. To carry out this feature of the invention, the casing sections are reduced at the last mentioned ends thereof and the screws are inserted through these reduced portions. The casing is adapted to fit the hand of the user and the operating handle is shaped to fit closely upon one side of the casing when in collapsed position, and this handle is formed with a longitudinally disposed superficial groove to receive the finger tips of an operator's hand. An improved locking means for the operating handle is provided and comprises a saddle shaped detent having a hook element adapted to coact with a hook element on the frame of the drive mechanism, the detent being pivoted upon a transversely disposed fulcrum member and being capable of being rocked into handle locking and unlocked position, the portion of the detent adjacent to the part of the operating handle engaged by the hand of the operator being depressed onto the handle when the detent is in unlocked position, so that a conscious effort must be made by the operator in order to lock the handle and the handle will therefore remain unlocked during use.

The drive mechanism of the dry shaver includes an arm on the operating handle and an eccentric rod connecting this arm to a disk-shaped member carrying a spring biased pawl. This member is coaxially arranged with an internally ratched gear wheel so that operation of the handle transmits intermittent impulses to the gear wheel. Reduction gearing connects the said gear wheel with a flywheel having an annular recess and a hardened eccentric disc therein, whereby a groove is defined in the flywheel and a rocker arm is operatively associated with the grooved flywheel and with a reciprocating cutter in the cutter head of the shaver.

A primary object of this invention is, therefore, to provide a dry shaver in which a divided casing is satisfactorily held closed upon a driving mechanism without any screws or other securing means being exposed on the exterior of the casing.

Another object of this invention is to provide an improved handle locking means which satisfactorily locks the handle in inoperative position adjacent to the casing of the shaver, and which

2

is tilted toward the portion of the operating handle grasped by the hand of the operator during use, whereby the unlocking action of the handle is greatly simplified and inadvertent locking of the handle during use is prevented.

Yet another object of this invention is to provide an improved driving mechanism, the features of which will be described hereinafter.

A specific object is to provide an improved flywheel and rocker arm construction, whereby space within the shaver is conserved and a highly efficient operation of the rocker arm is achieved.

And a last object to be specifically mentioned is to provide a dry shaver which is relatively inexpensive and practicable to manufacture; which is safe, comfortable and convenient to operate, and which will give generally efficient and durable service.

With these objects definitely in view, this invention resides in certain novel features of construction, combination and arrangement of elements and portions as will be hereinafter described in detail in the specification, particularly pointed out in the appended claims, and illustrated in the accompanying drawings which form a material part of this application, and in which:

Figure 1 is a perspective view of the assembled dry shaver, the figure indicating how the same is held in an operator's hand with the finger tips placed within a groove provided in the operating handle;

Figure 2 is a side elevational view of the shaver in inverted position and with one section of the casing removed, certain portions of the cutter head and the shield being shown in vertical section;

Figure 3 is a horizontal sectional view, taken substantially upon the irregular section line 3—3 in Figure 2 and looking upwardly in the direction of the arrows;

Figure 4 is an enlarged vertical sectional view, taken upon the line 4—4 in Figure 3 and looking in the direction of the arrows, a portion of the internally ratched gear wheel being broken away to show the internal construction thereof and the contiguous portions of a member carrying a spring biased pawl which is mounted upon the same shaft;

Figure 5 is a sectional view, taken substantially upon the line 5—5 in Figure 4;

Figure 6 is a front end elevational view, with the cutter head and cutter head shield removed and with other portions disposed toward the rear of those portions illustrated being also removed in order to improve the clarity of representation of those parts at the front end of the drive mechanism and frame therefor;

Figure 7 is a horizontal sectional view, fragmentary in character, designed to illustrate the drive wheel construction and those parts contiguous thereto;

Figure 8 is a three dimensional view showing the operating handle, the eccentric rod driven thereby and the internally ratcheted gear wheel and contiguous parts, portions of the frame for the drive mechanism being shown in phantom lines;

Figure 9 is a side elevational view of the flywheel and rocker arm, the shafts upon which these elements are mounted being shown in vertical section;

Figure 10 is a top plan view of the structure shown in Figure 9;

Figure 11 is an enlarged fragmentary detail view designed to show how the operating handle locking detent is mounted upon a transversely disposed raised fulcrum member on the operating handle;

Figure 12 is an enlarged fragmentary detail view of the forked end of the rocker arm used to drive the cutter in the cutter head;

Figure 13 is a sectional view, taken upon the line 13—13 in Figure 8 and designed to illustrate the construction of the means for holding the detent selectively in handle locking and unlocked positions; and

Figure 14 is a fragmentary three dimensional view of a portion of the frame for the drive mechanism, the figure being designed particularly to illustrate the construction and positioning of a hook element designed to coact with a hook element on the above mentioned detent.

Similar characters of reference designate similar or identical elements and portions throughout the specification and throughout the different views in the drawings.

Referring now to the drawings in detail, this dry shaver includes a casing comprised of two complementary sections 10 and 12 and adapted to house a driving mechanism having a pair of laterally disposed plate frame members 14. These frame members 14 are held together at the front end of the mechanism by screws 16 and at the rear end of the drive mechanism the frame members 14 are held together by a screw or bolt 18 and a complement of spacer sleeves 20 and 22 are associated with the screws 16 and 18 to maintain the frame members 14 properly spaced apart. The casing sections 10 and 12 are rabbeted marginally as at 24 and the rear ends of the casing sections are formed with internally disposed grooves 26 adapted to receive lugs 28 secured to the rear end of the drive mechanism and adapted to be received in the grooves 26 when the shaver is assembled thus holding the rear end portions of the casing sections together. In the embodiment illustrated, the lugs 28 are apertured to receive the screw 18 and the lugs are disposed between the frame members 14 and the sleeve 22. The front end portions of the casing sections 10 and 12 are reduced, as at 30, and the reduced portions are apertured at the front ends thereof to receive a block portion 32 of the cutter head generally indicated by the numeral 34. The cutter head block is held in position within the reduced portions 30 by a thumb screw 36 and a cutter head shield 38 fits over the cutter head 34 and is provided with dissimilar wings 40 adapted to fit snugly within correspondingly shaped dissimilar recesses in the sides of the casing sections 10 and 12, so that the shield will always be placed upon the shaver in the same position.

The frame members 14 terminate at the front end in inwardly offset portions 42 which are secured to the reduced portions 30 of the casing sections 10 and 12 by screws 46 shown in Figures

3 and 14 and the offset portions 42 are fastened to the front ends of the sections 10 and 12 by screws 46, and it is a feature of this invention that the cutter head shield 38 covers these screws 43 and 46 as well as the remaining portions of the front end of the internal mechanism of the shaver.

An operating handle 48 is pivoted upon the spacer sleeve 20 secured between the frame members 14 by a pair of the screws 16 and the handle 10 includes an arcuate bifurcated arm 52, which has a spacer sleeve 54 secured by a screw 50. A connecting rod 56 is pivoted on the sleeve 54 and extends rearwardly for pivotal connection, as at 58, with the disk-shaped member 60 carried by a sleeve bearing 62 freely rotatably mounted on the transverse shaft 64. The member 60 may be constructed with an outer thin disk plate 66 also carried by the sleeve bearing 62, and an internally ratcheted gear wheel 68 is coaxially mounted with the member 60 and this ratchet gear assembly may be filled with light grease to give silent operation. The member 60 carries a spring biased pawl 69 which engages successively 25 with ratchet teeth 71 on the gear wheel 68, as best illustrated in Figure 4, while this gear wheel 68 is in continuous mesh with a pinion 70 driving a second gear wheel 72 mounted upon another shaft 74. Another pinion 76 in continuous mesh 30 with the gear wheel 72 drives a third gear wheel 78 rotatably mounted upon a third shaft 80, and the third gear wheel 78 drives still another pinion 82 which is rigidly connected to a flywheel 84 by means of a sleeve bearing 86, best illustrated 35 in Figure 7.

The groove 88 is formed in the flywheel 84 by providing a recess on one side thereof and mounting an eccentric disk 90 within this recess. A rocker arm 92 is forked at one end as at 94 and 40 provided with shoes 96 frictionally engaging the disk 90 and this rocker arm is press fitted on a sleeve 97 pivoted upon a transverse shaft 98 and is provided with a forwardly extending portion 100 to engage a slot in a cutter 102 in the cutter head 34. The cutter head will also include a hair guiding member with a multiplicity of slots as indicated, while the cutter 102 will be biased forwardly against the member 104 by a plurality of spring biased balls 106 adjustably mounted in 50 the cutter head 34, the detailed construction of this cutter head being thought immaterial in this application.

The operating handle 48 is provided with a longitudinally disposed superficial recess 108 55 adapted to receive the finger tips of at least some of the fingers of an operator's hand, and the handle will be biased to pivot away from the casing of shaver by a helical spring 110 mounted coaxially on the sleeve 20 and having its ends 60 contacting the contiguous portion of the frame 14 (such as one of the inwardly offset portions 42) and the handle, in a manner which will be well understood without further description. The handle must be locked in inoperative position 65 adjacent to the casing when the shaver is not being used, and a saddle shaped detent 112 is provided on the forward end of the handle for this purpose. The detent 112 has a pair of lateral flanges or arms 114 and a longer more centrally disposed arm 116, all of plate character and the detent upper surface will preferably be transversely grooved to improve the ease with which the same may be moved by the thumb of an operator. The detent is secured to the handle by a 70 centrally arched bracket 118 secured to the un-

derside of the detent and enclosing a transversely disposed fulcrum member 120 which is preferably raised above the adjacent surface of the handle 48. The handle 48 will be apertured to accommodate the bracket 118 on each side of the fulcrum member 120. The arm 116 is provided with a hook element 122, positionally and dimensionally arranged to coact with a hook element 124 comprising an inwardly turned lug on one of the frame members 14. The arm 116 carried by the detent is slotted as at 126 to allow the detent to move with the handle without interference with the lug 124 when the detent is in unlocked position, and the arcuate bifurcated arm 52, on the corresponding side thereof, is also slotted as at 128. A leaf spring 130 is secured as by a screw 132 to the slotted side of the arm 52 and a portion of this spring extends into frictional contact with one surface of the arm 116, as indicated at 134 in Figure 13. A ball 136 or any other suitable knob-like projection, is provided on the arm 116 for selective engagement in a pair of depressions 138 in the spring portion 134, this selective engagement corresponding with the positioning of the detent in handle locking position and in unlocked position. It should be carefully noted that the portion of the detent 112 adjacent to the part of the handle 48 grasped by the hand of the operator will be tilted toward the handle when the detent is in unlocked position.

The operation of this invention will be clearly understood from a consideration of the foregoing description of the mechanical details thereof, taken in connection with the above recited objects and in connection with the drawings. Obviously all the objects recited are amply achieved by this invention and further description would appear unnecessary.

Variations from the embodiment described in this application may be resorted to without departure from the spirit of this invention and the scope of this invention should be determined only by a proper interpretation of the terms used in the subjoined claims.

Having described the invention, what is claimed as new is:

1. A hand operated dry shaver comprising a casing having two complementary hollow sections, a drive mechanism on a frame mounted within the casing and having an operating lever handle extending outside said casing, said sections having internal oppositely disposed flanges at the rear end of said casing and said frame having members engaging said flanges to hold the sections together at the rear end of the casing, said sections having reduced forward end portions, means securing said reduced portions together, a shaver head securable to said reduced portions and operably connected with said mechanism, and a head shield snugly fitting upon said sections and covering said securing means.

2. A shaver according to claim 1 and wherein said mechanism and frame are removable from said casing as a unit.

3. A hand operated dry shaver including a frame and having an operating handle, and a lock to hold the handle in retracted position comprising a saddle transversely pivoted on said handle, a detent on said saddle to engage a portion of said frame when the handle is in retracted position and said saddle is pivoted to one position, and means for releasably latching the saddle in said one position.

4. A hand operated dry shaver including a driving mechanism on a frame, an operating handle

pivoted on said frame and having an arm, a member rotatably mounted on the frame and carrying a pawl, a coacting internally ratcheted gear wheel rotatively mounted on said frame coaxially with said member, a connecting rod operatively connecting said arm with said member, a cutter operating rocker arm pivoted on said frame, a flywheel mounted in said frame and having an eccentrically mounted disk, said rocker arm having a fork frictionally and operatively engaging diametrically opposite sides of said disk, reduction gearing connecting said flywheel with said gear wheel and a spring biasing said handle in one direction.

5. In a dry shaver having a frame and a pivoted operating handle with a hand grip portion, lock means for the handle comprising a transversely disposed fulcrum member on the handle, a saddle shaped detent pivoted on said fulcrum member and having a hook element adjacent the pivotal connection of the handle, a coacting hook element on said frame, a leaf spring secured to said frame with a portion of the spring frictionally engaging said detent for releasably holding said detent selectively in handle locking and unlocked positions, the portion of said detent adjacent said hand grip portion of the handle being depressed against the hand grip portion when in said unlocked position.

6. In a shaver of the character described in claim 1 and wherein one longitudinal edge of the casing is shaped to fit the palm of a hand, and said operating handle is disposed on the opposite edge of the casing and has a longitudinally disposed superficial recess to receive the finger tips of an operator's hand.

7. A hand operated dry shaver including a frame and an operating handle and a lock to hold the handle in retracted position comprising a saddle transversely pivoted on the handle and a detent on said saddle to engage a portion of said frame when the handle is in retracted position and said saddle is pivoted to one position.

8. A hand operated dry shaver including a driving mechanism on a frame, an operating handle pivoted on said frame and having an arm, a member rotatably mounted on the frame and carrying a pawl, a coacting internally ratcheted gear wheel rotatively mounted on said frame coaxially with said member, a connecting rod operatively connecting said arm with said member, a cutter operating rocker arm pivoted on said frame, a flywheel mounted in said frame and having an eccentrically mounted disk, said rocker arm having a fork frictionally and operatively engaging diametrically opposite sides of said disk, reduction gearing connecting said flywheel with said gear wheel and a spring biasing said handle in one direction, said flywheel having an axial recess on one side thereof and larger than said disk, said disk being within said recess and said fork having flanges laterally extending into the groove defined between the periphery of the disk and the adjacent portion of the flywheel.

NORMAN J. TROUGHT.
